INVENTOR

Ernest Ashton
By his Attorney
Nelson W. Howard

UNITED STATES PATENT OFFICE.

ERNEST ASHTON, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

HEEL-BREAST-SCOURING WHEEL.

Application filed January 25, 1924. Serial No. 688,483.

This invention relates to scouring wheels and more particularly to devices for buffing or scouring the breast portion of the heel of a boot or shoe.

5 The invention is herein illustrated as embodied in a buffing or scouring device of the type shown in United States Letters Patent No. 1,048,957, granted December 31, 1912 on application of C. E. Graham. In the device 10 shown in this patent, an abrasive covering disposed in conical form is supported by a conical portion of compressed felt, and the base of the cone is supported in turn by metallic and non-metallic disks, these parts 15 being all mounted upon a supporting sleeve. While scouring devices of this type have been used extensively and successfully, some of the devices have been found to develop relative rotation of the various disks upon 20 the supporting sleeve with resulting distortion and injury to or destruction of the abrasive covering.

With this in view, an object of this invention is to provide an improved scouring wheel of this type constructed and arranged 25 so as positively to prevent the relative rotation of the component parts. This is accomplished in the illustrated construction in accordance with the present invention by interlocking the disks with one another and 30 one of the disks with the supporting sleeve.

A preferred form of the invention is illustrated in the accompanying drawing and 35 will be described in the following specification, but it will be understood that the scope of the invention is not limited to the exact showing and should be determined by reference to the accompanying claim when construed by reference to the prior art.

40 In the drawing, Fig. 1 is a side elevation partly in section of a scouring wheel constructed in accordance with the invention and showing the manner of its application to the breast portion of a heel.

45 Fig. 2 is a fragmentary perspective view with the parts separated to show the interlocking means.

The supporting sleeve 10 of the scouring wheel is intended to be mounted upon a rotating shaft 12 and is adapted to be held in 50 position thereon by means of the set screw 14. Near its outer end the sleeve has a somewhat larger raised seat portion 16 and is provided with an annular flange 18, as

in the device of the patent to which reference 55 has been made above. In assembling the device, a slight cupped steel disk 20 is forced on to the raised portion 16 of the sleeve 10 with a driving fit and in many cases this is found sufficient to prevent relative 60 rotation of the parts. A similarly cupped disk of leather or leatheroid 22 is next applied and may be glued to the inner face of the steel disk 20, if desired. It is noted that a reversed relation of the disks is found 65 in said Letters Patent. A foundation portion 24 of compressed felt, substantially conical in shape, is next forced on to the sleeve 10 and is glued to the outer surface of said sleeve and to the inner face of the leather 70 disk 22. In order to assist in holding the felt portion upon the sleeve, grooves 26 are provided into which the felt expands itself and to which it is attached by the glue previously applied. An abrasive covering 28 75 is then applied to the outer surface of the assembled parts and is held in position thereon by means of a knurled sleeve 30, which is screw threaded at 32 to the inner end of the supporting sleeve 10. It will be observed that the outer surface of the leather disk 22 forms an extension of the conical surface of the felt portion 24 and serves as a non-metallic, somewhat resilient peripheral support for the abrasive covering thereby 80 to avoid damage in case it accidentally contacts with the shank of the shoe. 85

Except as above noted the construction thus far described is substantially like that shown in the said Letters Patent, and in 90 spite of the precautions taken to prevent displacement of the parts, such displacement has occurred with sufficient frequency so that it becomes desirable positively to interlock the metallic disk 20, the leather disk 22 and the sleeve 10. To this end I have provided a substantially rectangular recess 34 in the inner periphery of the leather disk 22 and have struck up a complementally shaped tongue 36 from the steel disk 20 exactly in 95 position to enter the recess 34. Preferably this tongue will have parallel sides coacting with the sides of the recess. The entrance of this tongue 36 in the recess 34 securely interlocks the leather and the steel disks 100 against relative rotation. 105

As an additional safeguard, I have further provided an arrangement for inter-

locking the steel disk and hence the leather disk with the flange of the supporting sleeve 10. To this end a complementally shaped tongue or spur 38 has been struck up from 5 the annular flange 18 of the sleeve and positioned to enter the recess provided by the bending up of the tongue 36 thereby positively to prevent relative rotation of the steel disk 20 upon the supporting sleeve. 10 Preferably the spur 38, will have parallel sides coacting with the sides of the recess in the steel disk and will be substantially the same width as the tongue 36.

It will be apparent to those skilled in the 15 art that the tongue and the spur, as above described, preferably will be struck up before the parts have been assembled, but such a method of construction and the exact design of the tongue and spur, as illustrated 20 herein, are not absolutely essential to the successful operation of the invention.

Having thus described my invention, what I claim as new and desire to secure by Letters Patent of the United States is:—

25 A heel breast scouring wheel having, in

combination, a supporting sleeve provided with a flange at one end, a metallic disk arranged on said sleeve in proximity to the flange, a non-metallic disk extending beyond the periphery of the metallic disk and arranged on the sleeve in proximity to the metallic disk, resilient conical means arranged to cooperate with the edge of the non-metallic disk in supporting an abrasive covering, said means surrounding said sleeve and abutting said non-metallic disk at the base of the cone, said non-metallic disk being provided with a recess adjacent to the supporting sleeve, and means positively to prevent the relative rotation of the non-metallic disk and the supporting sleeve comprising a tongue struck up from the metallic disk to enter the recess in the non-metallic disk, and a spur struck up from said flange on the supporting sleeve to enter the recess formed by the bending of the afore-mentioned tongue.

In testimony whereof I have signed my name to this specification.

ERNEST ASHTON.
